UNITED STATES PATENT OFFICE

173,328

PACKAGE OF SPONGES

Lawrence J. Stoll, Westchester County, N. Y.

Application May 6, 1953, Serial No. 24,890

Term of patent 7 years

(Cl. D58—2)

To all whom it may concern:

Be it known that I, Lawrence J. Stoll, have invented a new, original, and ornamental Design for a Package of Sponges, of which the following is a specification, reference being had to the accompanying drawing, forming a part hereof.

Fig. 1 is a front perspective view of a package of sponges embodying my new design;

Fig. 2 is a rear perspective view thereof.

The dominant feature of my design resides in the portions shown in full lines.

I claim:

The ornamental design for a package of sponges, as shown and described.
